DESIGN FOR A PENCIL

Richard Kropsch, Budweis, Czechoslovakia, assignor to Koh-I-Noor Bleistiftfabrik L. & C. Hardtmuth, Budweis, Czechoslovakia, a Firm, composed of Frantisek Hardtmuth mladsi, Jan Herring-Frankensdorf, Dr. Bedrich Herling-Frankensdorf, Matylda Lamezan-Salins, Anna Hardtmuthova starsi, Anna Hardtmuthova mladsi, and Marie princezna de Rohen

Application April 28, 1937, Serial No. 69,015
In Czechoslovakia December 9, 1936

Term of patent 7 years

To all whom it may concern:

Be it known that I, Richard Kropsch, a citizen of Czechoslovakia, residing at Budweis, Grunwaldova, No. 545, Czechoslovakia, have invented a new, original, and ornamental Design for a Pencil, of which the following is a specification, reference being had to the accompanying drawing, forming a part thereof.

Figure 1 is an elevation of a pencil showing my new design.

Fig. 2 is a transverse section taken along the plane of line 2—2 of Fig. 1.

The characteristic features of the design reside in the provision of longitudinally-extending flutes of substantially semi-circular cross-section providing longitudinally-extending ribs of substantially semi-circular cross-section, and in having the tops of the ribs of contrasting color to the fluted areas.

I claim:

The ornamental design for a pencil, as shown and described.

RICHARD KROPSCH.
